UNITED STATES PATENT OFFICE

SAMUEL WEIDENFELD, OF NEW YORK, N. Y.

GAME DEVICE

Application filed March 26, 1928. Serial No. 264,886.

This invention relates to a new and amusing device in the nature of a target game especially adapted to amuse children or to improve the shooting abilities of adults.

5 The invention has for an object the provision of an air gun adapted to shoot a bullet at a target embodying an automatic mechanical means of notifying the shooter or player that the bull's eye of the said target has been 10 hit by the bullet.

A further object of the invention is to notify the shooter that the target card has been hit by the bullet.

Another object of the invention is to provide 15 a target of simple construction and arrangement of parts comparatively cheap to manufacture and assemble.

Fig. 1 is a front elevational view of my improved target.

20 Fig. 2 is a similar view showing the target after the bull's eye has been hit.

Fig. 3 is a similar view to that shown in Fig. 1, illustrating another form of my improved target.

25 Fig. 4 is a similar view showing the target after the bull's eye has been hit.

Fig. 5 illustrates a further form of my improved target.

Fig. 6 is a similar view to that shown in Fig. 30 5 after the bull's eye has been hit.

Fig. 7 is a still further form of my improved target.

Fig. 8 is a side elevational view of the gun and bullet as embodied in my improved device.

35 Fig. 9 is a vertical sectional view, taken on the line 10—10 of Fig. 10.

Fig. 10 is a rear elevational view of Fig. 9.

40 Fig. 11 is an enlarged fragmentary rear elevational view illustrating in particular a further development of my improved target.

Fig. 12 is a vertical sectional view taken on the line 12—12 of Fig. 11.

45 As here embodied my improved target game comprises an air gun 10, or rifle, such as generally employed to shoot a bullet 11, of spherical shape preferably of lead and which is secured to the free extremity of the flexible member 12 attached to the air gun. The 50 above mentioned air gun may be compara-

tively small so as to be safely used by children or may be constructed so as to shoot the bullet 10 at considerable range and velocity rendering my improved game device instructive to adults as a medium of target practice. 55

My improved target comprises a body member 13, of card board, fibre board, wood, metal or any suitable composition, material, formed or cut square.

A pair of flexible members 14 and 15 are 60 extended through the tubular rivets 16 and 17, or grommets respectively, secured to the upper portion of the said body member and provided for the purpose of suspending the target from a limb of a tree, or any suitable 65 support, or so as to permit the target to be held suspended from the hands of a person.

The body member 13 has formed therein a central aperture 18, of circular shape and has affixed thereto a plurality of rings 19 of any 70 desired various and different colors, concentric with the aperture 18, so as to provide a bull's eye.

The indicator card 20 of rectangular shape, is slidably mounted vertically in the bracket 75 21, secured to the rear upper portion of the said body member by the above mentioned rivets 16 and 17. The bracket 21 having its central portion formed or bent somewhat outwardly from the body member 10 so as to 80 form an opening adapted to slidably receive the said indicator card.

The tension spring 22 is secured to the bracket 23 attached to the lower portion of the card 20, by the rivet 24 and to the outwardly formed or bent element 25 of the first mentioned bracket 21. The clip 26 is secured to the central lower portion of the body member 10, by means of the rivet 27, and is provided with an outwardly formed or 85 bent element 28 adapted to freely engage in an elongated opening 29 formed in the lower portion of the indicator card.

The above described construction is such as will normally permit the said card to be 95 held directly at the rear of the body member 10, in an unextended position, so as to allow the numeral 30, affixed to the said card to be visual through the aperture 18 formed in the said body member. The above de- 100

scribed construction is also such as will permit the said card to be released from the clip 26, when the target is struck in the center or in the aperture 18, which scores a bull's eye, so as to permit the numeral 30', identical with the above mentioned numeral 30, to be visual above the body member 10, as a means of notifying the shooter that a bull's eye has been scored. It is obvious that the tension spring will urge the indicator card upwardly, when the said card is released from the clip 26, as above set forth.

In Figs. 3 and 4 of the accompanying drawing, I have shown a body member 31 formed or cut circular, so as to conform to the concentric rings 19 affixed thereto. The indicator card 32 having affixed thereto, at the upper portion thereof any desired object 33, representing preferably a turkey, visible when a bull's eye has been scored, for the purpose as above set forth.

In Figs. 5 and 6 of the accompanying drawing, I have shown a somewhat larger body member 34, cut or shaped square, and having formed therein apertures 35 and 36, circular shape, similar to the above mentioned aperture 18, positioned at either side of the aperture 18. Indicator cards 37 and 38 are similarly mounted on the body member 34 directly at the rear of the apertures 35 and 36, respectively, as a means of visibly exposing the objects 39 and 40, affixed to the upper portions of the cards 37 and 38 respectively, for the hereinbefore desired purpose.

In Figs. 7 of the accompanying drawing, I have shown a target considerably larger than the above described targets, consisting of a body member 41, rectangular shape, horizontally disposed, and having affixed thereto and extended therefrom at the bottom thereof, a pair of supports 42 and 43, having therein extended extremities pointed as at 44 and 45, respectively as a means of supporting the target in the ground.

The body member 41 has affixed thereto a plurality of bull's eyes 46 arranged in a horizontal row in proximity to the upper portion thereof, and has also affixed thereto a plurality of bull's eyes 47, similarly arranged in a horizontal row in proximity to the lower portion of the said body member. The said bull's eyes 46 and 47 are relatively staggered, so as to prevent interference of the indicator cards provided from the above described purpose, when in a visibly exposed position above the upper portion of the body member.

In Figs. 11 and 12, I have shown secondary indicator card 48 hinged as at 49 to the bracket 50 secured as at 51 to the lower portion of the body member 13. A supporting strip 52 is secured as at 53 to the free extremity of the card 48 constructed preferably of comparatively soft pliable metal, so as to be readily bent or formed to hold the card

in any desired angular upwardly inclined position toward the body member 13. The above described construction is such as will permit the said card to assume a downwardly inclined position as designated by the reference numeral 54 when my improved target is hit by the above mentioned bullet, the latter described notifying the shooter that the target was hit, although a bull's eye was not scored which will tend to increase and hold the interest of the shooter, the said card being visible from the front of the target.

Having thus described my invention what I claim as new and desire to secure by United States Letters Patent is:—

In a game device of the class described, a target with a central aperture representing a bull's eye, a bracket located near the top of the target and having end portions secured on the target and a central projecting portion forming a passage with a portion of the target, a card flat against the target and crossing the bull's eye and having its top end normally engaging in said passage and its bottom end held, so that when the card is hit thru the bull's eye a portion thereof moves for freeing the held bottom end, while the upper portion remains motionless and engaged in the said passage for directing subsequent movement of the card, said central projecting portion being formed with a projecting tongue forming a support for a means for moving the card.

In testimony whereof I have affixed my signature.

SAMUEL WEIDENFELD.
